PUMP

Sumner Wiltse, Detroit, Mich.

Application June 11, 1937, Serial No. 147,595

7 Claims. (Cl. 103—152)

This invention relates to reciprocating pumps of the type having a delivery or outflow stroke actuated by a resilient member, such as a spring, and a suction stroke induced against the action 5 of said resilient member by an actuating unit receiving its power from some outside source. Such pumps are particularly adapted for use in pumping fuel for internal combustion engines since the spring actuated outflow stroke renders 10 the pump automatically operable in proportion to the demand for fuel.

The greater number of present day pumps used in automobile practice are mechanically driven from some rotating part of the motor 15 and, therefore, operate at a speed proportional to that of the motor. It is true, however, that the speed of the motor is not necessarily properly controlling for the speed of the pump and often the speed is too great, pumping fuel at a rate 20 which is not required and resulting in overheating of the pumped fuel with consequent loss thereof by evaporation.

The use of a reciprocating pump having a spring actuated outflow stroke results in automatically reducing the action of the pump when the amount of fuel delivered exceeds requirements, since when the pressure built up in the outflow line exceeds the spring pressure the pump 25 will no longer reciprocate. However to gain full 30 advantage from the use of this type of pump it is important that sufficient capacity be available for peak requirements and at the same time avoid pulsating flow. This object, however, cannot be satisfactorily obtained by merely increasing the 35 size of one reciprocating unit to increase capacity.

It is, therefore, a primary object of the present invention to provide a pump having a primary pumping element with an outflow stroke so actuated 40 as to be resiliently responsive to outflow pressure as aforesaid, but having the added feature of a secondary pumping element controlled in its reciprocation by the primary pumping element but alternating in suction and delivery 45 strokes whereby a more nearly constant flow may be maintained at peak requirements while maintaining a practical rate of reciprocation for both pumping elements.

As one possible embodiment it is a further 50 object to provide fuel pump for internal combustion engines with primary and secondary reciprocating elements of the aforementioned character having their suction strokes induced by a source of suction made available by other means 55 associated with the engine such for instance as

is disclosed in my copending application Serial Number 147,596 filed June 11, 1937.

It is a further object to construct a pump of the aforementioned type having alternately operated diaphragms in separate pumping chambers both operated by suction, one of said diaphragms operating as a primary pumping diaphragm, the other of said diaphragms operating as a secondary pumping diaphragm, but both operating in proportion to the amount of fuel 10 required.

It is another object to make available a reciprocating pump having dual pumping elements having suction strokes induced by suction and delivery or outflow strokes induced by spring 15 pressure or other resilient means, said elements being alternately connected to atmosphere and to a source of suction by valve means operated by the movement of one of said pumping elements.

It is a further object to provide a pump with dual pumping diaphragms, each of which is actuated in its pumping stroke by resilient means, such as a spring, and in its suction stroke by the operation of suction in a chamber provided on 25 the side of each diaphragm away from the fluid being pumped, the suction admitted to each chamber being controlled by a two way valve operated by the movement of one of the diaphragms.

It is a further object to provide a duplex type of pump in which instead of employing a double acting cylinder and piston, the duplex function is performed by primary and secondary pumping elements but which are not physically interconnected and having valve means for controlling the action of both pumping elements operated by the strokes of the primary pumping element.

The above and other objects of the invention will appear more fully from the following detailed description of one possible mechanical embodiment of the invention which has been found satisfactory in actual operation, and by reference to the accompanying drawings forming a part hereof and wherein:

Fig. 1 is a vertical cross section through the pump showing the pumping chambers, the dual diaphragms, and the suction control valve.

Fig. 2 is a section taken on the line 2—2 of Fig. 1 and shows the inlet and outlet conduits 50 through the two pumping chambers, together with the check valves required to effect the dual operation of the two pumping chambers.

Fig. 3 is a view taken substantially on the line 3—3 of Fig. 1 and shows a top view of the operat- 55

- ing parts of the control valve for alternately connecting suction to the two diaphragms.
- Fig. 4 is a section taken on the line 4—4 of Fig. 3 and shows a side view of the operating parts of the suction control valve.
- Fig. 5 is a section taken on the line 5—5 of Fig. 4 and shows a cross section through the two valve units which control the alternate connection of suction and atmosphere with the two pumping chambers.
- Fig. 6 shows a modified form of the pump in which an auxiliary manually operated mechanism is provided for alternately actuating the two pumping elements in a suction stroke.
- Referring to the drawings, particularly to Fig. 1, a central pump casting 10 preferably circular in shape is provided with an inlet conduit 11 having suitable threaded connection for a fuel pipe, not shown. This inlet conduit 11, in the form of a drilled hole, extends into the central portion of the pump casting 10 and communicates with two inlet check valves designated generally by the reference characters 12 and 13, see Fig. 2, through suitable cross-drilled conduits 14 and 15. The inlet check valve 12 communicates with a lower pumping chamber 16 formed by a recess in the lower face of the central pump casting 10; while the inlet check valve 13 communicates with an upper pump chamber 17 formed by a similar recess in the top surface of the central pump casting 10. The communicating opening from the check valve 12 to the lower pump chamber 16 is shown at 18 in Figs. 1 and 2, while the communicating conduit to the upper pump chamber 17 is indicated by the full lines at 19 in Fig. 1. The above described system of inlet conduits provides a common inlet into the casting 10 with separate check valves 12 and 13 opening into the pump chambers 16 and 17 respectively.
- The detailed construction of both check valves 12 and 13 is similar, as shown in Fig. 2, there being a specially designed screw 21 with a projecting end 22 for retaining a spring 23 which holds a valve member 24 against a seat formed at the end of each of the conduits 14 and 15. Provision for assembly of the check valves is accomplished by drilling from the outside of the casting 10 and providing suitable threads therein for the screws 21.
- There are separate outlets for both pump chambers 16 and 17, the outlet from the lower pump chamber 16 being shown at 26 in Fig. 1 and Fig. 2, and the outlet from the upper pump chamber 17 being shown dotted at 27 in Fig. 1. The conduit 26 leading from the lower pump chamber 16 connects with the conduit 28 which leads into a main outlet conduit 29 extending across the casting 10 and shown in both Figs. 1 and 2. Another conduit 31 connects the conduit 27 from the upper pump chamber 17 with the main outlet conduit 29. Outlet check valves 32 and 33 are provided for operation with the conduits 28 and 31 respectively, thereby affording an outlet check valve from the upper and lower pump chambers into the main outlet conduit 29. Both outlet check valves 32 and 33 are of a construction similar to that used for the inlet check valves described above, a specially designed screw 34 with end projection 36, spring 37 and valve member 38 being provided for each valve. The outlet conduit 29 has suitable threads at its end for connection of a fuel pipe, not shown.
- A pumping diaphragm unit completes each of the pumping chambers 16 and 17, the lower diaphragm being designated by the reference char-
- acter 39 and the upper diaphragm by the reference character 40. Each of these diaphragms is gripped between the flange formed on the edge of the central pump casting 10, and the flange of a suction and spring retaining chamber member 41, for the lower pump chamber, and a similar member 42 for the upper pump chamber, the flanges being designated as 43 and 44 respectively. Suitable screw connecting means are provided around the flanges 43 and 44 as indicated at 46 in Fig. 2. The lower diaphragm 39 has a stem 47 secured at its center by provision of two large washers 48 and 49 on opposite sides of the diaphragm 39, securely fastened by threads in the end of the stem 47 and by a nut 51. The lower casting 41 is of such shape as to form a chamber 52 and to retain a spring 53 therein. The stem 47 is retained for reciprocating movement in a suitable guiding boss 54 extending into the chamber 52. One end of the spring 53 reacts against the lower end of the chamber 52 and the other end reacts against the washer 49 and tends to push the diaphragm 39 upwardly. The lower end of the stem 47 is mounted to reciprocate in a bearing 56 provided in a lower cover member 57 as shown in Fig. 1. A notch 58 is turned in the stem 47 for operating a valve mechanism which will later be described in detail. A valve chamber 59 is formed below chamber 52 and is connected therewith by an opening 61. The valve chamber 59 is closed at its lower end by the lower cover member 57 in which there is mounted a dual valve mechanism, as shown in Figs. 4 and 5.
- Continuing with the description of upper diaphragm 40 and its operating spring, the said diaphragm 40 is secured between the flange 44 of the casting 42 and the central casting 10. A stem 62 is secured to the center of the diaphragm 40 by a pair of washers 63 and 64 on opposite sides of said diaphragm, the washers being held in place on the stem 62 by a suitable nut such as shown at 65. In a manner similar to that employed for the lower unit, the stem 62 is mounted for reciprocating movement in a boss 66 extending downwardly into the upper diaphragm operating chamber 67 which is formed in the casting 42. As shown in Fig. 1, the chamber 67 is of such shape as to retain a spring 68, one end of which reacts against the upper end of the chamber and the opposite end reacts against the washer 64 and tends to force the diaphragm 40 downwardly. A conduit 73 leads from the lower valve unit to the chamber 67. It is through this conduit that suction is provided for the actuation of the upper pumping unit in a manner which will appear more fully later in this description.
- The fitting 69 shown at the top of Fig. 1 is for the purpose of closing the opening provided for the reciprocating stem 62 and also when removed this member 69 serves as a handle for manual operation of the top pump chamber unit. The attachment of the handle is accomplished by threading the screw threaded end 71 of fitting 69 into the opening 72 made available when the fitting 69 is removed. With the fitting 69 thus mounted a manual movement thereof in up and down direction actuates the diaphragm 40 to manually operate the top half of the pump.
- Proceeding now with the description of the two way valve unit shown in detail in Figs. 1, 3, 4 and 5, there is shown in Fig. 5 an opening at 74 for connecting a supply pipe from a source of suction. The drilled conduit 76, shown in Fig. 5, affords a communicating passage for the suction into chamber 59 when the valve positions are as

shown in Fig. 5 through the opening 71. The necessary valve members are carried by plugs 81, 82 as shown in Fig. 5, threaded into the cover 57 by two threaded openings 78 and 79 provided in the cover 57. The plug 81 has a valve seat provided at each of its ends and carries a valve stem 83 with suitable valve closure members, 84 and 85 at its ends. The stem 83 is of sufficient length so that the distance between the valve closure members 84 and 85 is greater than the length of the plug 81. Also the stem 83 is of less diameter than the drilled opening 86 in the plug 81, in which the stem is slidably mounted. Radial ports 86a (Fig. 4) connect drilled opening 86 with opening 76 (Fig. 5) through annular space 77b (Fig. 4). Therefore, when the valve member 83 is in the upward position as shown in Fig. 5, the lower valve closure 84 is sealed while the upper closure is unsealed and the suction line is thus allowed to communicate with the chamber 59 through the opening 77. However, when the member 83 is in the downward position, the lower closure 84 is opened and the suction communicates with conduit 87 below the valve plug 81 while the valve member 85 has closed the opening 77 from communication with the chamber 59. The other valve plug 82 shown in Fig. 5 is similarly provided with a central hole 89 in which the valve stem 88 reciprocates. A chamber 82a is formed between the lower face of the valve plug 82 and a closure plug 82b, this chamber 82a being open to the atmosphere thru a conduit 90 shown in Figs. 1 and 5. A valve closure member 91 is secured at the end of the stem 88 with surfaces so shaped that when stem 88 is in its downward position a conduit 90, leading to chamber 59, is open to the atmospheric chamber 82a while conduit 92 leading to upper pump chamber 67 is closed. However, with the valve stem 88 in its upward position, the conduit 82 is open to the atmospheric chamber 82a, thus supplying atmospheric pressure to the upper pump chamber 67 through conduits 93 and 73. Each of the valve stems 88 and 83 project upwardly as shown in Fig. 4 and are connected together by a pin 94, which projects through a toggle lever member 96, as shown in Figs. 1, 3 and 4. Another toggle lever member 97 is mounted on a post 98, and the two toggle members 96 and 97 are operatively connected by a member 99 which fits in two notches in their ends as shown in Fig. 1. The members 96 and 97 are also connected by a spring 101 and are so positioned that movement of the yoked end 102 of the toggle member 97 will cause a change in position of the member 96 from the upward location shown in Fig. 1 to an opposite downward position. This movement is a quick "snap" when the toggle passes a definite point in its movement. It is understood that the yoke 102 fits around the notch 58 of the stem 47 so that downward movement of the stem 47 will cause the toggle to assume the opposite position to that shown in Fig. 1 and close the valve 85 so that suction is shut off from the lower chambers 52 and 59 and admitted to the upper pump chamber 67. It is also noted that atmospheric pressure is admitted to the opposite chamber, not connected with the suction line, by the movement of the valve stem 88 also actuated by the toggle 96.

The manner in which the pump operates is as follows: A line from some unit producing suction, such for instance, as described in my co-pending application, Serial No. 147,596, filed June 25, 1937, is connected at 14 as shown in Figs.

1 and 5. With the pump parts and toggle lever unit in the positions shown in Fig. 1, the valve stems 83 and 88 will be held in the position shown in Fig. 5 so that suction made available at 14 will exhaust air from the lower pump chamber 52 thru opening 61, chamber 59, opening 77 and conduit 76. The lower pumping diaphragm 39 is shown at the beginning of its suction stroke in Fig. 1 and as the suction is applied in the chamber 52 the diaphragm 39 operates to perform its downward or suction stroke. The stem 47 is carried with the diaphragm 39 and moves the toggle member 97 downward by contact with yoke 102, and near the end of the suction stroke the toggle unit will snap to the opposite position. When this happens the position of member 96 will push the valve stems 83 and 88 downward and will connect the suction at 14 thru conduits 76, 87, 93 and 73 to exhaust air from the upper pump chamber 67. At the same time change in the position of closure member 91 at the end of stem 88 will connect chambers 59, 52 with atmospheric chamber 82a thru conduit 90.

It is understood that the reciprocation of the diaphragms 39 or 40, in their respective pumping chambers 16 and 17, produces inflow of fluid by action of the respective inlet check valves 12 and 13 (Fig. 2) when the direction of movement of said diaphragms 39 or 40 is such as to increase the volume of the chambers 16 or 17. Conversely, when the direction of movement of the diaphragms 39 or 40 is in a direction to reduce the volume of the pumping chambers 16 or 17, the result will be an outflow of the fluid through the outlet 23 by action of the respective outlet check valves 32 and 33 (Fig. 2).

It is apparent that the action of diaphragms 39 and 40 is alternating and the action of the diaphragm 40 is indirectly controlled by the movement of diaphragm 39 to which the valve control 40 is directly attached.

It is also to be noted that one of the most important advantages of this type of pump is that the springs are acting against the resistance to outflow of the fluid being pumped. In other words, when the resistance to outflow becomes greater than the force exerted by the spring 53 on the lower pumping diaphragm the pump will no longer exert a pumping stroke to force fluid into the line. In this manner the pumping action is momentarily stopped when the consumption of fuel is reduced and there is no continuous pumping with its attendant heating and evaporation of the fuel such as occurs in many continuously reciprocating pumps. With the use, however, of the combination of the upper diaphragm 40 working alternately with the lower diaphragm 39 a sufficient pumping ability is assured at all times when a large quantity of fuel is required. This cooperative alternating action is assured because the action of the upper diaphragm is controlled in its action by the lower diaphragm in such manner that the upper pumping diaphragm is operative to perform a pumping stroke while the lower diaphragm is performing its suction stroke. It is apparent that the use of double alternating diaphragms controlled by one of them makes practical the use of this type of pump in many conditions of operation requiring a considerable range of fuel consumption, since the double stroke assures a sufficient capacity to take care of all demands while avoiding pulsating flow.

The modified form of pump shown in Fig. 6 is provided with mechanism for manual operation 75.

in addition to the automatic operation which has been previously described. In this modification the invention is particularly adapted for use in aircraft work where it is often necessary to have a hand operated pump for supplying fuel because of the usual practice of running the motors entirely out of fuel at certain times to reduce fire hazard. It is intended that the pump shown in Fig. 6 be located in or near the pilot's compartment so that handle 125 will be in a convenient position for operation. The central pump casting 126 shown in Fig. 6 is of identical construction with the central pump casting shown on Fig. 1 of the drawings. In fact, the entire mechanism for automatic operation and the dual diaphragm construction is the same as in the pump shown in Fig. 1. However, there is added in the construction shown in Fig. 6 necessary connecting parts to secure a manual operating linkage, denoted generally by the reference character 127, to stems 128 and 129 which are connected to actuate with upper and lower pumping diaphragms 130 and 131 in a suction stroke. For the purpose of manually actuating the top of the diaphragm 130 a hollow shaft 132 is mounted to reciprocate in a suitable boss 133 projecting from the top of the pump and suitably threaded to receive a nut 134 adapted to retain conventional packing 135. The hollow shaft 132 projects above the nut 134 and is pivotally mounted to a lever 136, the end of which is secured to a link 137. The hollow shaft 132 fits over and surrounds the stem 128 which is connected to the upper diaphragm 130. A pin 138 is secured to the stem 128 and projects outwardly therefrom into slots 139 and 140 in the sides of the hollow shaft 132. It will be noted that this means of connection of the stem 128 to the hollow shaft enables the diaphragm 130 to be automatically reciprocated by the suction mechanism when the shaft 132 is in the position as shown in Fig. 6 since the relative position of the slot 140 and the pin 138 allows reciprocation of the stem 128. However, when the lever 136 is pulled away from the pump, i. e. upwardly, as shown in Fig. 6, it will pull the diaphragm 130 upwardly also against the action of the diaphragm spring which normally urges the pump in a direction for a delivery stroke. In other words, the actuation of the lever 136 provides manual means for producing a suction stroke, the delivery strokes still being spring actuated as in automatic operation.

A similar connecting means for manual operation is provided at the lower side of the pump for connection to the stem 129 in the form of a hollow shaft 141, a nut 142, a lever 143 and a link 144, a pin 145 secured to stem 129 being provided to operate in the slots 146 and 147. It is apparent that the actuation of the lever 143 away from the pump will effect a suction stroke of the diaphragm 131 against the delivery stroke spring as previously mentioned in connection with the upper diaphragm operating lever 136.

For the purpose of normally holding the levers 136 and 143 in the position nearest the pump so that the slots in the hollow shafts 132 and 141 will not interfere with automatic operation of the pump, a tension spring 148 is provided to connect the two ends of the levers 136 and 143 and therefore to normally urge them toward each other thereby producing the desired position of the levers. For the purpose of providing mechanism for placing the pump in condition for manual operation a pair of links 149 and 150 are pro-

vided with a pivotal connection 151, the combined lengths of the links 149 and 150 being greater than the distance between the ends of the levers 136 and 143 when in the position nearest the pump as held by the tension of spring 148. Therefore, when the handle 125 is pushed toward the pump as shown in Fig. 6 to straighten out the links 149 and 150 the result is to spread the ends of the levers 136 and 143 away from each other against the tension of the spring 148. The position of the slots in the hollow shafts 132 and 141 will then be such that up and down movement of the handle 125 will alternately actuate the diaphragms 130 and 131 in a suction stroke, the delivery stroke in each case being accomplished by the spring which normally operates the diaphragms in this stroke.

Although I have described my invention as applied to a particular illustrative combination found practical in actual use, it is apparent that various changes and modifications may be made without departing from the fundamental principles herein disclosed. I do not desire to limit myself to the specific embodiments but rather to the scope of the following claims.

I claim:

1. In a suction operated pump, a primary pumping element, a secondary pumping element movable independently of said primary pumping element, a common inlet and a common outlet conduit for both of said pumping elements, a suction valve operated by said primary pumping element controlling alternate admission of suction to both elements through said conduits, and a second valve interconnected with said suction valve for controlling alternate admission of atmospheric pressure to said primary and secondary pumping elements.

2. In a pump, a central pump casting having a recess on two sides thereof, inlet and outlet check valves mounted in said casting and connecting with said recesses, independently movable diaphragms covering each of said recesses to form two pumping chambers, members shaped to form suction chambers on the opposite side of said diaphragms from said recesses and attached to said central casting in a manner such as to grip the edges of said diaphragms, springs mounted in said suction chambers to normally urge said diaphragms inwardly of said pumping chambers, conduit connections to said pumping chambers including an atmospheric vent and a suction connection to said chambers, and valve means to alternately subject said suction chambers to said suction connection and to atmospheric pressure whereby said diaphragms are alternately flexed outwardly against the action of said springs to produce suction strokes in said pumping chambers.

3. In a pump, a pair of independently movable pumping elements, resilient means for actuating said pumping elements for outflow strokes, suction operated means for actuating said pumping elements for suction strokes, conduit connections to said pumping elements including an atmospheric vent for each of said elements, a source of suction, a two way valve connected to be operated by movement of said pumping elements to alternately connect said source of suction with said pair of pumping elements through said conduit connections and to alternately open said atmospheric vents thereby to produce alternate operation of said pumping elements.

4. In a pump, a reciprocable primary pumping element for a delivery or outflow stroke, suc-

- tion operated mechanism for actuating said primary pumping element in a suction stroke against the action of said resilient means, a secondary reciprocable pumping element movable independently of said primary pumping element, conduit connections to each of said pumping elements including an atmospheric vent for each of said elements, and means under control of said primary pumping element to cause said suction operated mechanism to operate said secondary pumping element in a suction stroke and to alternately subject said pumping elements to suction and atmospheric pressure through said conduit connections.
5. In a pump, a pair of independently movable pumping elements, suction operated means actuating said pumping elements for suction strokes, resilient means actuating said pumping elements for outflow strokes, a source of suction, a member connected to reciprocate with one of said pumping elements, a two-way valve connected thereto, conduit connections to each of said pumping elements including an atmospheric vent for each of said elements from said two-way valve to said suction operated pumping elements, a toggle for operating the said two-way valve, a projection from said toggle contacting said reciprocating member whereby said two-way valve is operated when said reciprocating member and said pumping element complete a predetermined stroke thereby to alternately operate said pair of suction operated pumping elements through said conduit connections and to alternately subject said pumping elements to atmospheric pressure thru said atmospheric vent.
6. In a pump a primary pumping element hav-
- ing a delivery stroke actuated by spring pressure, a housing around said pumping element forming a suction chamber, a source of suction, a valve member including an atmospheric vent for connecting said source of suction or atmospheric pressure to said suction chamber to operate said pump for a suction stroke against the action of said spring at the end of said spring actuated delivery stroke, a secondary pumping element, movable independently of said primary pumping element, a housing around said secondary pumping element forming a suction chamber, a valve member including an atmospheric vent for connecting said secondary pumping element with said source of suction or atmospheric pressure to actuate said secondary pumping element in a suction stroke, a member actuated by said primary pumping element whereby said valve is actuated to connect said source of suction with said secondary pumping element at the end of the suction stroke of said primary pumping element.
7. In a pump of the type in which the delivery or outflow stroke is actuated by a spring pressed element characterized by a primary pumping element and a secondary pumping element movable independently of said primary pumping element, said secondary pumping element alternately set in operation for a delivery stroke at the end of the delivery stroke of said primary pumping element, and mechanism comprising a member actuated by said primary pumping element for controlling the operation of both of said elements.
